BUFFER SPRING FOR RAILWAY
PASSENGER CARSGarth G. Gilpin, Riverside, Ill., assignor to Union
Metal Products Company, Chicago, Ill., a cor-
poration of Delaware

Application March 20, 1933, Serial No. 661,646

23 Claims. (Cl. 105—14)

The invention relates to railway passenger train cars, and more particularly to a mechanism positioned between the end wall of the car and the upper part of the diaphragm face plate, and an object of the invention is to provide a mechanism which yieldingly retains the upper part of the face plate at a predetermined distance from the end wall of the car and in the longitudinal center of the car when the car is not coupled to another car, but allows the face plate to move toward the end wall of the car when the car is coupled to another car and also to accommodate the movements of the car when running.

My device also yieldingly allows the face plate to assume an oblique position when the car is rounding a curve and/or to move laterally of the car under service conditions. Furthermore, the device allows the face plate to move vertically relative to the end wall of the car to allow for the wearing of the lower face plate supports and/or allows one end of the spring to move vertically relative to the other end of the spring because frequently the lower support at one side of the face plate wears more than the support at the other side of the face plate. Furthermore, the face plates and the buffering mechanism are not always accurately installed on the car. My invention accommodates all of the above mentioned movements of the face plate without binding any of the associated parts and at the same time returns the face plate to a predetermined relative position to the end wall of the car when free to do so.

In the drawing:

Fig. 1 is a perspective of the end of a railway car showing the usual relation between the end wall, diaphragm face plate and upper buffer mechanism.

Fig. 2 is an enlarged plan view of the upper buffer mechanism in normal position.

Fig. 3 is the same as Fig. 2 with the upper buffer mechanism compressed.

Fig. 4 is the same as Fig. 2 showing the diaphragm face plate in an oblique position.

Figs. 5, 6 and 7 show the relation between the end post and buffer mechanism.

In the drawing the usual parts of the car are shown, such as the end wall 2; diaphragm 3 and diaphragm face plate 4.

The drawing shows the usual semi-elliptic spring 6 attached to the diaphragm face plate 4 in the usual (8) or any desirable manner. The brackets 10 are mounted upon the end wall 2 of the car substantially equi-distant on each side

of the center line of the car and each bracket is provided with a bearing 12. The leaf spring 6 is provided with a separate shoe 14 which slidably engages the bearings 12 of the brackets and preferably a wearing plate 16 is provided between the bearing surfaces of the brackets and the shoes so that the entire wear is taken by the shoes and wearing plates. The brackets are preferably provided with spaced apart substantially horizontal flanges 18—20 and a bolt 22 passing through apertures in these flanges retains the shoe 14, the spring 6 and also the wearing plate 16, if used, in cooperative relation with each other so that in order to disassemble the device for replacements or repairs it is only necessary to remove the bolt 22. These flanges 18—20 also are guideways for the shoe 14. The shoe is preferably provided with a stop 24 which engages the bolt 22 to limit the movement of the shoe toward the center of the car. By this means the movement of the face plate away from the car is restricted to a predetermined amount. The shoe 14 may be provided, if desired, with means to engage the bracket to restrict this movement of the shoe toward the center of the car. (Not shown.) While a semi-elliptic spring is usually used and seems preferable, nevertheless, my device would work with a full elliptic spring or with a flat leaf spring; that is, where the spring comprises a plurality of flat leaves of various lengths.

Each shoe 14 is provided with a guide 30 which is substantially parallel with the bearing surface 12 of the shoe so that the bolt 22 retains the shoe in close proximity to the wearing surface when the spring is under compression. (This occurs when the car is not coupled to another car.)

In the drawing I have shown a simple method of attaching the shoe to the end of the spring which consists of providing a laterally extending lip 32 on the spring which is loosely positioned between the spaced apart portions 34—36 of the shoe. In this arrangement the shoe is hooked on to the end of the spring by simply oscillating it a little about the lip 32, after which the shoe 14 is put in place upon the bracket 10 and the bolt 22 inserted. The distance between the spaced apart portions 34—36 of the shoe is greater than the thickness of the lips 32 of the spring whereby one end of the spring may move higher than the other end thereof without binding the spring in the shoe. The vertical height 38 of the spring bearing 12 of the shoe is greater than the vertical width 40 of the spring 6 whereby the spring may

move bodily vertically relative to the shoes (and to the wall of the car).

This arrangement also allows relative movement between the spring and the shoe in a horizontal plane and/or in a vertical plane substantially parallel to the wall of the car and/or in a vertical plane normal to the wall of the car, thus it will be seen that the spring is attached to the shoe to allow movement between the two parts in substantially any combination of directions.

The shoe is provided with a bearing 44 for the spring which is preferably elongated to obtain a surface bearing and the spring is provided with a similar portion engaging said bearing.

15 In my arrangement the wear caused by the friction between the moving parts is taken by the shoe and the bracket (or by the wearing plate if used) and not by the spring, which is very desirable, because the spring is very expensive in 20 comparison with the shoe which can be made of cast metal or the bracket or wearing plate which can be made of steel plate.

The accompanying drawing illustrates the preferred form of the invention, though it is to be understood that the invention is not limited to the exact details of construction shown and described, as it is obvious that various modifications thereof, within the scope of the claims, will occur to persons skilled in the art.

30 I claim:

1. In a buffer mechanism for a railway car diaphragm face plate, the combination of brackets mounted upon the car in spaced relation, each comprising a web forming a bearing and spaced apart flanges forming guideways, a shoe slidably engaging the web of each bracket between the respective guideways, each bracket provided with a pin passing through apertures in said flanges, and a leaf spring having each end loosely attached to one of said shoes, said elements associated and arranged so that the pins retain the spring in engagement with the shoe.

2. In a buffer mechanism for a railway car diaphragm face plate, the combination of brackets mounted upon the car in spaced relation, each comprising a web forming a bearing and spaced apart flanges forming guideways, a shoe slidably engaging the web of each bracket between the respective guideways, each bracket provided with a pin passing through apertures in the flanges, and a leaf spring having each end loosely attached to one of said shoes, said elements associated and arranged so that the pins retain the shoes in engagement with the brackets and retain the spring in engagement with the shoe.

3. In a buffer mechanism for a railway car diaphragm face plate, the combination of brackets mounted upon the car in spaced relation, each comprising a web forming a bearing and spaced apart flanges forming guideways, a shoe slidably engaging the web of each bracket between the respective guideways, each bracket provided with a pin passing through apertures in the flanges, and a leaf spring having each end loosely attached to one of said shoes, said elements associated and arranged so that the pins retain the shoes in engagement with the brackets, retain the spring in engagement with the shoe and limit the slidable movement of the shoes relative to the brackets.

4. In a buffer mechanism for a railway car diaphragm face plate, the combination of brackets mounted upon the car in spaced relation, each of

said brackets having a flat web, a shoe provided with a substantially flat surface slidably engaging the web of each bracket, and a leaf spring having each end attached to one of said shoes, said elements associated and arranged whereby a spring movement of the spring causes the shoes to slide upon said webs, respectively, though permitting oscillating movements of the shoes relative to the ends of the spring in a horizontal plane whereby a surface contact is maintained between said surfaces and said webs during service movements of the mechanism.

5 5 In a buffer mechanism for a railway car diaphragm face plate, the combination of brackets mounted upon the car in spaced relation, a shoe 15 provided with a substantially flat surface slidably engaging the web of each bracket, and a leaf spring having each end attached to one of said shoes, said elements associated and arranged whereby a spring movement of the spring causes 20 the shoes to slide upon the bracket bearings though permitting oscillating movements of the shoes relative to the ends of the spring in a vertical plane.

6. In a railway car having a wall element and a diaphragm face plate element, a buffer mechanism positioned between said elements comprising a leaf spring having its medial portion attached to one of said elements, said spring provided with a separate shoe at each end thereof 30 provided with a substantially flat surface having a slidable engagement with the other of said elements so that the ends of the spring are spaced apart from said other element during service movements of the mechanism whereby 35 wear caused by movement of the spring relative to said other element is taken by the shoes.

7. In a railway car having a wall element and a diaphragm face plate element, a buffer mechanism positioned between said elements 40 comprising a leaf spring having its medial portion attached to one of said elements, said spring provided with a separate shoe at each end thereof 45 provided with a substantially flat surface having a slidable engagement with the other of said elements so that the ends of the spring are spaced apart from said other element during service movements of the mechanism whereby wear caused by movement of the spring relative to said other element is taken by the shoes, and 50 means to retain the shoe in sliding engagement with said other elements.

8. In a railway car having a wall element and a diaphragm face plate element, a buffer mechanism positioned between said elements 55 comprising spaced apart brackets on one of said elements, a leaf spring having its medial portion attached to one of said elements, said spring provided with a separate shoe at each end thereof 60 provided with a substantially flat surface having a slidable engagement with the other of said elements so that the ends of the spring are spaced apart from said other element during service movements of the mechanism whereby wear caused by movement of the spring relative to said other element is taken by the shoes, each 65 of said brackets having spaced apart substantially horizontal walls forming guideways for the slidable shoe, and means to retain the shoe in sliding engagement with the brackets.

9. In a railway car having a wall element and a diaphragm face plate element, a buffer mechanism positioned between said elements comprising spaced apart brackets mounted upon one of said elements, a leaf spring provided with a 75

ment, which means also retains the spring in hooked relation to said shoes.

20. In a railway car having a wall element and a diaphragm face plate element, a buffer mechanism positioned between said elements comprising a leaf spring provided with a separate shoe at each end thereof provided with a flat surface having a slidable engagement with one of said elements said spring having its medial portion attached to the other of said elements, each of said shoes attached to the spring to allow relative movement between the spring and the shoe in a horizontal plane whereby a surface contact is maintained between said surfaces and the adjacent element during service movements of the mechanism.

21. In a railway car having a wall element and a diaphragm face plate element, a buffer mechanism positioned between said elements comprising a leaf spring provided with a separate shoe at each end thereof provided with a flat surface having a slidable engagement with one of said elements and having its medial portion attached to the other of said elements, each of said shoes attached to the spring to allow relative movement between the spring and the shoe in a horizontal plane and in a vertical plane substantially parallel to the wall element.

22. In a railway car having a wall element and a diaphragm face plate element, a buffer mechanism positioned between said elements comprising a leaf spring provided with a separate shoe at each end thereof provided with a flat surface having a slidable engagement with one of said elements and having its medial portion attached to the other of said elements, each of said shoes attached to the spring to allow relative movement between the spring and the shoe in a horizontal plane, in a vertical plane substantially parallel to the wall element and in a vertical plane normal to the wall element.

23. In a railway car having a wall element and a diaphragm face plate element, a buffer mechanism positioned between said elements comprising a leaf spring provided with a separate shoe at each end thereof provided with a flat surface having a slidable engagement with one of said elements and having its medial portion attached to the other of said elements, each of said shoes attached to the spring to allow relative movement between the spring and the shoe in a vertical plane substantially parallel to the wall element and in a vertical plane normal to the wall element.
